UNITED STATES PATENT OFFICE.

JOSEPH KRELL, OF BERLIN-PANKOW, GERMANY.

PRINTING MACHINE.

Application filed March 31, 1927, Serial No. 180,028, and in Germany May 12, 1926.

My invention relates to printing, for instance, addressing machines as described in my U. S. Patent No. 1,532,890, and it is an object of my invention to provide means by which any printing plate which is presented to the printing platen in the normal operation of the machine, may be skipped, and to this end I provide a switch adapted to be operated by the attendant to break the circuit of the electromagnet controlling the printing platen which is normally closed by a selective switch as often as a plate is presented at the printing station so that when the attendant operates the switch, the plate which is then presented, will be skipped.

It will be understood that under these conditions, that is, when the skipping switch is operated for a given plate presented at the station, the control electromagnet is not excited notwithstanding the operation of its selective switch and so this plate will be skipped.

By these means the possibilities of the machine are increased as compared with the prior machine referred to.

The skipping switch may be of any suitable design and construction but is preferably made as follows: It is operated by a separate pedal or handle, connected with an automatic detent which retains the switch in its "break" position so that it will not return to "make" position immediately its handle is released, and with an automatic mechanism which is under the control of the printing arm to throw out the detent, and provided with automatic means, for instance, a spring, for returning it to its "make" position after it has been freed by the throwing out of its detent.

In the drawings, part of an addressing machine is shown to illustrate my invention by way of example.

Fig. 1 is a section of the machine at the printing station and at right angles to the direction in which the printing plates are presented to the printing platen,

Figs. 2, 3, and 4 illustrate, on a larger scale, details of the skipping switch,

Fig. 2 is an elevation of the switch viewed as in Fig. 1, or in the direction of the arrow II in Fig. 3, showing its "make" position,

Fig. 3 is a section on the line III-III in Fig. 2,

Fig. 4 shows the upper part of the switch in its "break" position.

Referring now to Fig. 1, 1 is the table of the machine, 2 is its printing arm, 3 the

shaft on which the arm is reciprocated by means of a rod 30, connected to disk 31, the latter being driven by suitable clutch mechanism on the main drive shaft 32. 4 is the printing station, 5 is a selective switch of known type which is operated by projections on the lower faces of the printing plates, 6 is an electromagnet, 11 is part of the circuit connecting it with the selective switch 5, 7 is the armature of the electromagnet 6, 2 is a lever on the shaft 3 which is moved with the printing arm by friction and is arrested when the armature 7 is attracted, 9 is a head at the end of the printing arm, and 8 is the printing platen which is slidably carried in the head and connected with the lever 2 by a system of links and levers so as to be pushed into operative position out of the head 9 when the lever 2 has been so arrested. 2' is an extension of the printing arm 2 below the shaft 3 which moves on after the lever 2 has been arrested so that the motion of the printing arm is not interfered with by the lever 2, the extension 2' moving on in the direction 75 against the arrow 9', and the printing platen 8 is forced against the paper on the printing plate which is at the printing station 4.

When the printing arm 2 returns to its initial position, the electromagnet 6 is de-energized and drops its armature 7 which then releases the arm 2 and the arm 2 is free to move with the extension 2' until the extension strikes an abutment 10 on the frame of the machine. The lever 2 is now in its initial position as shown in Fig. 1, the printing platen 8 is returned into its initial position, and the machine is ready for another operation.

12 are contacts at which the circuit 11 is broken, 13 are contact springs on a switch body 15, which springs are adapted to make contact at 12, 12, the body being of insulating material, 14 is a plunger to which the body is secured, 16 is a sleeve on the frame of the machine in which the plunger 14 is slidably carried, 17 is a spring in the sleeve which tends to hold the plunger in its upper end position in which the contact springs and fixed contacts complete the circuit 11, 18 is a Bowden cable secured to the plunger 14, 19 is a pedal to which the other end of the cable is secured, 20 is its fulcrum, and 21 is a tubular standard on which the fulcrum is carried. Preferably the tube 21 also supports the pedal—not shown—for throwing in the machine.

22 is a shoulder machined in the plunger

14, 23 is a preferably U-shaped, detent adapted to cooperate with the shoulder 22, 24 is its fulcrum on the sleeve 16, 25 is a downward extension of the detent, 26 is a spring tending 5 to hold the detent 23 engaged with the shoulder 22 as indicated by the arrow 27, and 28 is a push bar pivoted to the extension 2' of the printing arm 2 and adapted to throw out the detent 23.

- 10 As long as the pedal 19 is not operated the circuit 11 is closed at the contacts 12, 12 by the springs 13 and the machine operates as the machine described in my prior patent. When, however, the attendant desires not to 15 print any of the plates which are presented at the printing station in due course, she will depress the pedal 19, moving the switch 15 down into the "break" position, Fig. 4, and allowing the detent 23 to engage the shoulder 20 22 under the action of its spring 26. The downward motion of the plunger 14 under the action of the Bowden cable 18 and against the spring 17, consequently, causes the contacts 12 to be opened and the circuit 11 to be 25 broken, deenergizing the electromagnet 6 and preventing printing of the plate which is to be skipped.

The skipping switch will remain in its position after the pedal has been released 30 30 while the detent 23 remains in position on the shoulder 22. When the skipped plate has been moved past the printing station and the next plate has been presented, and this plate is to be printed as usually, the pedal 19 35 is not operated and the push bar 28 will throw out the detent 23 when the printing arm has returned to its initial position, allowing the

spring 17 to move the switch 15 into its "make" position as shown in Fig. 2.

To facilitate identification of the printing 40 plates which should be skipped, the plates are preferably provided with marks of any kind, for instance, coloured strips so that the attendant is able at a glance to pick out the plates which must be skipped. 45

I claim:

1. A printing machine comprising a frame, a continuously oscillating printing arm fulcrumed on said frame, means for rocking said arm, an impression platen on said arm, mechanism for actuating said impression platen and operatively connected with said means, an electromagnetic control for said mechanism, and means for selectively rendering inoperative said control independently of said 55 means for rocking said arm.

2. A printing machine comprising a frame, a continuously oscillating printing arm fulcrumed on said frame, means for rocking said arm, an impression platen on said arm, mechanism for actuating said impression platen and operatively connected with said means, an electromagnetic control for said mechanism, a circuit connected with said electromagnetic control, a switch adapted to break 65 said circuit, an automatic detent for locking said switch in its "break" position, automatic means for returning it into its "make" position, and means operatively connected with said printing arm for throwing out said de- 70 tent.

In testimony whereof I affix my signature.

JOSEPH KRELL.
